UNITED STATES PATENT OFFICE.

WADE HAMPTON DE FONTAINE, OF NEW YORK, N. Y.

CARBURETER FOR KEROSENE AND THE LIKE.

1,172,263.

Specification of Letters Patent. Patented Feb. 22, 1916.

Application filed January 24, 1914. Serial No. 814,077.

To all whom it may concern:

Be it known that I, WADE HAMPTON DE FONTAINE, a citizen of the United States, and resident of the city of New York, county 5 of New York, State of New York, have invented a new and useful Improvement in Carbureters for Kerosene and the like, of which the following is a specification.

My invention relates to carbureters for 10 internal combustion engines using a liquid hydro-carbon as a fuel; more particularly my invention relates to carbureters of the character specified in which petroleum, kerosene, or other fuel oil is combined with water 15 and used as a fuel.

It is the object of my invention to provide 20 a carbureter of the type specified which shall be capable of use with any internal combustion engine as above referred to for the purpose of reliably, economically and easily vaporizing and otherwise preparing petroleum, kerosene or other fuel oil in combination with water so that it can be at once employed in the production of an explosive 25 mixture for the operation of said engine.

In my application S. N. 764,490, filed in 30 United States Patent Office, April 30, 1913, I have shown and described a carbureter of the general type just referred to. The carbureter herein disclosed is an improvement upon and a development of the carbureter of this previously filed application.

The carbureter about to be described will perhaps be understood a little more readily 35 if its characteristics are first set forth very broadly and generally. Briefly, therefore, I may say that my improved carbureter provides a casing, substantially symmetrical as to a vertical plane, and containing at 40 one side receptacles for water and gasolene respectively, and upon the other side a receptacle for the petroleum or other fuel oil. Each of these receptacles is provided with a suitable float valve for maintaining the supply 45 of liquid at the requisite height. At the center of the casing is a mixing tube having three spray nozzles for water, gasolene and oil respectively, these tubes being so arranged as to discharge against the under- 50 side of a suitably shaped baffle member, by which the spray is more completely broken up and vaporized. Each of these spray nozzles is adjustable by means of a needle valve having a head outside of the casing, and a 55 suitable valve or cock determines whether fuel oil or gasolene shall be used.

Above the mixing tube there is provided a mixing chamber the outlet of which is controlled by a butterfly valve operated by an external lever arm suitably connected to 60 a moving part of the engine. A lateral inlet is provided with a spring controlled inwardly opening puppet valve for the auxiliary air supply.

A jacketing passage surrounds the mixing chamber and opens into a similar passage around the mixing tube and the fuel oil receptacle and connects, by a suitable pipe connection, to the bottom of the mixing tube below the spray nozzles. The beginning of 70 this jacketing passage is connected to a sleeve surrounding the exhaust pipe and the heated air thus supplied heats the mixing chamber and mixing tube so as to better vaporize the spray material, heats the fuel 75 oil chamber so as to more quickly raise the temperature of said oil and vaporize it, and then is utilized as the primary air supply.

My improved carbureter will be described in detail by referring to the drawings in 80 which—

Figure 1 represents a side elevation of a preferred form of the completely assembled carbureter; Fig. 2 represents a central longitudinal section through the carbureter along the line 2—2 of Fig. 4; Fig. 3 represents a horizontal section along the line 3—3 of Fig. 2; Fig. 4 represents a horizontal section taken along the line 4—4 of Fig. 2; and Fig. 5 represents a central transverse section 90 along the line 5—5 of Fig. 1.

In the drawings, 1 represents a main casting so cast as to provide the mixing tube 2 running from top to bottom of the casing. In the form shown this mixing tube is a 95 Venturi tube of usual type. On one side of the Venturi tube are two chambers 3 and 4 for water and gasolene respectively having a separating partition 5. On the other side of the Venturi tube is a single circular 100 chamber 6 for fuel oil as for example, kerosene. A cap 7 fits snugly upon the underside of the casing so as to close the Venturi tube at the bottom. A second casting 8 fits upon the main casting 1 and is provided with a 105 mixing chamber 9 in continuation upwardly of the Venturi tube. This casting is further provided with a jacketing passage 10, which nearly surrounds the mixing chamber and opens at its bottom into a similar jacketing 110 passage 11 surrounding the Venturi tube and the fuel oil chamber; air from a sleeve sur-

rounding the exhaust pipe is admitted by inlet 12 and leaves by a pipe 13 which joins the jacketing passage outlet to the bottom of the cap 7. Mixing chamber 9 receives an auxiliary air supply through a lateral opening 14, which leads from a laterally disposed cup-shaped chamber 15, closed at the bottom by an inwardly opening puppet valve plate 16, kept in tension by two springs 17 and 18, the former being a small diametered rather stiff spring guided by and held in compression by a spindle 19, itself adjustably held in a milled head 20 which has screw engagement with and closes the top of the chamber 15. The underside of this head has a central boss which engages the top of the larger diametered spring. By changing the adjustment of the spindle 19, so as to alter the tension of the smaller diametered spring, very large changes in the pressure required to open the puppet valve are effected, whereas, if the milled head 20 be turned, independently of the spindle, very small adjustments of this puppet valve tension are brought about. The milled head is held in any desired position by means of a spring click 21 held in a lug forming part of the cup-shaped receptacle.

The main casting 1 is provided with a two-way valve 22, a passage 23 leading from the valve to the fuel oil chamber, a second passage 24 leading from the valve to the gasoline chamber and a pair of passages 25 and 26 leading from the valve to the kerosene and gasoline nozzles 27, 28 respectively. By shifting the two-way valve from one side to the other it is, therefore, possible to connect either the gasoline chamber or the kerosene chamber to its own fuel nozzle as the case may be, and only one of these nozzles, obviously, can be connected at a given time.

The two fuel nozzles 27, 28, and a third nozzle 29 which connects with the water chamber 3 are equally spaced about the axis of the Venturi and supported by the casing 1 so as to discharge against the underside of a baffle member 30. This baffle member is circular and its bottom is provided with an upwardly convexed annular surface. The spray from the nozzles upon striking this surface, is still further broken up. The several nozzles are provided with adjustable needle valves so that the quantity of fuel may be regulated.

The mixing chamber is provided with a suitable butterfly valve 31 which may be connected by an external crank arm 32 to a suitable moving part of the engine where-by the supply of vaporized fuel may be regulated.

The operation of my invention is as follows: The flange 33 is bolted or otherwise suitably connected to the fuel supply pipe of the engine and the inlet 12 is joined by a

suitable pipe to a special sleeve surrounding the exhaust. To start up the engine, the three way cock 22 is first turned so as to connect the gasoline nozzle 27 with the gasoline receptacle, and the engine is turned over. The air supply, heated by the exhaust, passes through the heat jacketing passages 10 and 11 and heats the walls of the mixing chamber and of the Venturi tube; it also heats the fuel oil receptacle, raises the temperature of said oil and finally passes through pipe 13 into the bottom of the Venturi and is sucked up and through the mixing chamber. In the Venturi this air is filled with the gasoline and water spray drawn from the gasoline and water nozzles, which spray is very finely broken up by the impact against the bottom of the baffle member 30. The heated walls of the Venturi and the mixing chamber tend to still more finely break up this spray. As the mixture passes through the mixing chamber 9 its amount is controlled by the butterfly valve 31 actuated by the engine and the quality of the mixture is varied by the addition of auxiliary air through the puppet valve 16 and lateral opening 14. The several floats maintain the requisite level of water and gasoline and the needle valves are adjustable so as to permit the right amount of fluid to pass therethrough. The tension of the puppet valve 19 is suitably adjusted.

After the engine is run on gasoline for a few minutes the petroleum or other fuel oil will have been sufficiently heated to permit of the two-way valve 22 being thrown to the other limit of its motion, thus cutting off the gasoline and substituting the petroleum. Owing to the increased temperature of this fuel oil it will now readily vaporize and is sprayed out through its own nozzle 28 against the baffle member 30 just as was the gasoline. By thus having entirely separate and distinct passages leading from gasoline and fuel oil chambers respectively to separate and distinct spray nozzles and having said passages and nozzles controlled by the single two-way valve these spray nozzles may be adjusted once and for all whereas when, as in my prior application referred to, the same nozzle is used for both gasoline and fuel oil the nozzle must be readjusted each time the change is made from gasoline to fuel oil or vice versa.

Instead of taking my main air supply from a sleeve surrounding the exhaust and passing it through the several jacketing passages, I may, if I prefer, disconnect the pipe 13 and admit atmospheric air directly to the bottom of the Venturi through cap 7. In this case inlet 12 may be connected direct to the exhaust so as to permit exhaust gases to pass through the jacketing passages thereby affording a greater supply of heat for the

vaporization of the kerosene or other fuel oil.

It will be noted that the Venturi extends well up into the mixing chamber which flares upwardly away from the Venturi at a point just a little above the baffle member 30. In order to prevent condensed fuel from collecting in the space between the mixing chamber and the outer surface of the Venturi, holes 32' are pierced through the latter at the bottom of the space referred to; these holes taper downwardly and centrally and allow the condensed fuel to flow back into the mixing tube.

While I have described a preferred form of my invention, various modifications may be made without departing from the spirit thereof and within the scope of the following claims:

20 I claim:

1. In a carbureter of the class described, a mixing chamber, a mixing tube, a fuel oil chamber, a jacketing passage adjacent to said tube and chambers and a removable

pipe connecting said passage with the bottom and inside of said tube so that the air supply for said tube may either first pass through said passage or be independent thereof.

2. In a carbureter of the class described, a central mixing tube, a water chamber and a gasolene chamber upon one side of said tube and separated by a partition wall, a fuel oil chamber upon the other side of said tube, a mixing chamber upon said mixing tube, a jacketing passage outside of and adjacent to the mixing chamber and mixing tube and substantially surrounding the fuel oil chamber, and a removable pipe between said jacketing passage and the bottom inside of the mixing tube.

In testimony whereof I have hereunto set my hand in the presence of two subscribing witnesses.

WADE HAMPTON DE FONTAINE.
